US00D805540S

(12) **United States Design Patent** (10) **Patent No.:** **US D805,540 S**
Kim et al. (45) **Date of Patent:** **** Dec. 19, 2017**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Eunjoo Kim**, Seoul (KR); **Zion Kwon**, Seoul (KR); **Jungeui Seo**, Daegu (KR); **Jinki Jung**, Seongnam-si (KR)

(73) Assignee: **SAMSUNG ELECTRONICS CO., LTD.**, Gyeonggi-Do (KR)

(**) Term: **15 Years**

(21) Appl. No.: **29/571,913**

(22) Filed: **Jul. 22, 2016**

(30) **Foreign Application Priority Data**

Jan. 22, 2016 (KR) 30-2016-0003338

(51) **LOC (10) Cl.** **14-04**

(52) **U.S. Cl.**

USPC **D14/486**

(57) **CLAIM**

The ornamental design for a display screen or portion thereof with graphical user interface, as shown and described.

DESCRIPTION

FIG. 1 is a front view of a display screen or portion thereof with graphical user interface according to a first embodiment, showing our new design; and,

FIG. 2 is a front view thereof according to a second embodiment.

The outermost broken lines illustrate the display screen or portion thereof and form no part of the claimed design. The remainder of the broken lines illustrate portions of the graphical user interface and form no part of the claimed design.

1 Claim, 2 Drawing Sheets
